UNITED STATES PATENT OFFICE.

ARTHUR W. BERRESFORD, OF WESTFIELD, NEW JERSEY.

THEATER-DIMMER.

SPECIFICATION forming part of Letters Patent No. 628,685, dated July 11, 1899.

Application filed February 27, 1899. Serial No. 706,967. (No model.)

To all whom it may concern:

Be it known that I, ARTHUR W. BERRESFORD, a citizen of the United States, and a resident of Westfield, in the county of Union and State of New Jersey, have invented a new and useful Improvement in Theater-Dimmers, of which the following is a specification.

In obtaining the lighting effects used in connection with theatrical productions to produce the illusions called for by the piece it is necessary to mix the various colors of light and to obtain gradual changes for varying the quantity of light of each color by variation in the amount emitted by each source of light. This is accomplished by introducing a gradually increasing or decreasing resistance into the lamp-circuit, and thus controlling the current supplied.

In the construction of apparatus for producing the above effects, which apparatus are generally known as "theater-dimmers," it has been the practice to assemble or bank the resistance-plates into a rigid whole by passing tie-rods through the plates and into supporting-frames therefor and separating the several plates by short lengths of pipe surrounding the rods between the plates. In this structure it was necessary to remove more or less of the apparatus to remove any one of the resistance-plates if for any cause the removal of such plate became desirable. In operation it becomes necessary to move several of the independent contact-levers at the same time to produce a certain effect. This is ordinarily accomplished by providing a master-lever shaft which is mounted in brackets carried by the resistance-plates, which shaft communicates motion to the several contact-levers by rigid connections with segments mounted to rotate freely on the axes of the contact-levers, which segments are arranged to interlock with the said contact-levers.

One object of my invention is to obviate the necessity of knocking down the structure to remove any one of the resistance-plates, the said plates in my improved structure being independently mounted in the supporting-framework.

Another object of my invention is to mount the master-lever shaft in the frame independently of the resistance-plates in such a manner as to permit the said shaft to be adjusted

laterally and vertically without interfering with the said plates, to compensate for any distortion in the framework due to derangement in shipment, unevenness of setting, &c. This structure enables any one of the plates to be removed without removing the shaft and without disturbing any of the remaining plates, and, further, obviates the difficulties which occur in attempting to align the holes in the several plates so as to mount the shaft therein as has heretofore been customary.

A further object is to provide flexible connections between the master-lever shaft and the several contact-lever segments or wheels, so as to insure the easy operation of the said levers by the master-lever without any tendency to bind or cramp.

A still further object is to provide means for reversing the flexible connection between the master-lever shaft and any of the several contact-levers, so that when the master-lever is swung in one direction certain of the contact-levers will be caused to swing in the reverse direction when interlocked with their segments or wheels to produce certain desired effects.

A practical embodiment of my invention is represented in the accompanying drawings, in which—

Figure 1 represents my improved apparatus in end elevation. Fig. 2 is a side view of the same. Fig. 3 is a transverse vertical section in the plane of the line 3 3 of Fig. 2. Fig. 4 is an enlarged detail sectional view of one form of insulating adjustable coupling for securing together the free ends of the flexible connections, and Fig. 5 represents a detail view showing the manner of crossing the flexible connections to reverse the movement of the contact-lever segment or wheel.

The resistance-plates are denoted by A, and the supporting-frame therefor comprises upright frames B and cross-bars B' B² B³ which cross-bars serve to connect the upright frames. Two of these upright frames B, are shown in the accompanying drawings as end frames; but it is to be understood that there may be one or more intermediate upright frames to strengthen the structure where a large number of resistance-plates are carried by the frame, if found desirable.

The several cross-bars B' B² B³ may be

5 bolted firmly to the upright frames B, so as to produce a rigid structure. In the accompanying drawings I have represented the upper cross-bar B' as a flat bar, the rear lower cross-bar B² as a T-bar, and the front cross-bar B³ as an L-bar.

10 I have represented a bank of four resistance-plates A in the accompanying drawings, but there may be a greater or lesser number, according to different requirements. Each of these plates A is removably secured to the several cross-bars independently of the other plates in the following manner: The plate A rests upon the lower cross-bars B² B³ and 15 is secured to the front lower cross-bar B³ by bolts b, which pass through the said cross-bar and through lugs a, extended laterally from the front of the lower edge of said plate. The plate is secured to the rear lower cross-bar B² 20 by means of bolts b', which pass through the said cross-bar and through lugs a', extended laterally from the bottom of the rear edge of the said plate. The plate is also bolted to the upper cross-bar B' by means of bolts b², which 25 pass through the said cross-bar and through lugs a², projecting laterally from the top of the rear edge of the said plate.

30 The contact-lever is denoted by C, and it is mounted on a stub-axle a³, projecting from about the middle of the plate A. The contact-lever-controlling segment or wheel is denoted by D, and it is mounted to rock freely upon the stub-axle a³ and is fitted to be interlocked with the said contact-lever. The means 35 which I have shown for interlocking the lever and segment or wheel consists of a dog c, arranged to enter a notch d in the periphery of the segment or wheel D. This dog c is connected to an operating-handle c', located at the handle of the contact-lever. The dog may 40 be held in its raised position for releasing the lever from the segment or wheel D by means of a ring c², which embraces the handle c' and the handle of the contact-lever. The contact-lever C may be provided with the usual 45 contact-plates c³ c⁴, arranged to travel over the upper and lower series of contact-points a⁴ a⁵.

50 In order to move several of the independent contact-levers C at the same time, I provide a master-lever shaft E, which shaft is provided with a plurality of wheels or segments e, mounted fast thereon, corresponding to the contact-lever segments or wheels D.

55 The shaft E is provided with a master-lever e', which extends upwardly in the present instance to a point above the frame between one of the end upright frames B and the adjacent resistance-plate. However, the master-lever might project from the said shaft 60 at any place along the bank of resistance-plates as found desirable.

65 The segments or wheels e impart a rocking movement to the wheels or segments D through flexible connections F. Each of these flexible connections F preferably consists of a wire rope divided into two sections having their adjacent ends clamped within insulat-

70 ing-couplings G, so that there will be no electrical connection between the upper segment or wheel and the lower segment or wheel. This insulating-coupling G is arranged to take up any slack in the rope F, as it is essential that the said flexible connection or rope shall be very taut, so as to insure the proper operation of the contact-lever controlled thereby. In the present instance the 75 ends of the rope are held in position within the coupling by means of set-screws g g'. When it is desired to move the contact-lever in the same direction as the movement of the master-lever, the rope leads from one side of the periphery of the lower segment or wheel to the same side of the upper segment or wheel. When it is desired to cause the contact-lever to move in the opposite direction 80 to the movement of the master-lever, the ends of the upper section of the rope are crossed, so that the rope leads from the periphery of one side of the lower segment or wheel to the periphery at the other side of the upper segment or wheel. This flexible connection is 85 preferably wire rope or other suitable material which will not stretch.

90 The master-lever shaft E is mounted to rock in the upright frames B in such a manner 95 that it may be adjusted both laterally and vertically to accommodate itself to any unevenness in the setting of the frame. In the present instance this adjustment is secured by providing each end of the shaft with a 100 bearing-sleeve e², which sleeve is engaged on each side by adjusting-screws e³, carried by a vertically-adjustable bracket e⁴, carried by one of the upright frames B. In the present instance these brackets e⁴ are made vertically 105 adjustable by providing them with vertically-elongated slots e⁵, through which bolts e⁶ pass into engagement with the said upright frame.

110 In the structure as above described the master-lever shaft is mounted in the frame entirely independent of the several resistance-plates, so that any of the said resistance-plates may be removed without disturbing the said shaft.

115 What I claim is—

1. A theater-dimmer comprising a suitable supporting-frame, a plurality of resistance-plates, a contact-lever and contact-points carried by each plate independently of adjacent plates and means for securing each plate to the supporting-frame in removable adjustment, substantially as set forth.

120 2. A theater-dimmer comprising a supporting-frame consisting of upright frames and cross-bars connecting the said frames, a plurality of resistance-plates, a contact-lever and contact-points carried by each plate independently of adjacent plates and means for securing each plate to the said cross-bars in removable adjustment, substantially as set 125 forth.

130 3. A theater-dimmer comprising a supporting-frame, resistance-plates carried thereby, contact-levers for the resistance-plates and a

master-lever shaft connected with the said contact-levers, the said shaft being mounted in the supporting-frame independently of the said resistance-plates, substantially as set forth.

4. A theater-dimmer comprising a supporting-frame, a plurality of resistance-plates carried thereby, contact-levers for the plates, a master-lever shaft connected with the said contact-levers and mounted in the frame independently of the resistance-plates, and means for adjusting the shaft laterally and vertically, for the purpose set forth.

5. A theater-dimmer comprising a supporting-frame, resistance-plates carried thereby, contact-levers, segments or wheels arranged to interlock with said levers, a master-lever shaft mounted in the frame, segments or wheels carried thereby and flexible connections between the contact-lever segments or wheels and the master-lever shaft segments or wheels, substantially as set forth.

6. A theater-dimmer comprising a supporting-frame, resistance-plates carried thereby, contact-levers, contact-lever segments or wheels arranged to interlock with the contact-levers, a master-lever shaft mounted in the frame, segments or wheels carried by the said shaft, flexible connections between the con-

tact-lever segments or wheels and the master-lever-shaft segments or wheels, and means for reversing the said flexible connections whereby one or more of the contact-lever segments or wheels may be caused to rock in the reverse direction to the movement of the master-lever-shaft segments or wheels, substantially as set forth.

7. A theater-dimmer comprising a supporting-frame, resistance-plates carried thereby, contact-levers therefor, contact-lever segments or wheels arranged to interlock with the said levers, a master-lever shaft mounted in the frame, segments or wheels carried thereby, flexible connections between the shaft segments or wheels and the contact-lever segments or wheels comprising upper and lower sections and means for insulating the upper and lower sections of the flexible connections and adjusting their tension, substantially as set forth.

In testimony that I claim the foregoing as my invention I have signed my name, in presence of two witnesses, this 23d day of February, 1899.

ARTHUR W. BERRESFORD.
